UNITED STATES PATENT OFFICE.

HERBERT ROTHWILL, OF SCOBAY, MONTANA.

SHEET-GUIDE FOR CYLINDER-PRESSES.

1,273,276.

Specification of Letters Patent. Patented July 23, 1918.

Application filed December 1, 1917. Serial No. 204,881.

To all whom it may concern:

Be it known that I, HERBERT ROTHWILL, a citizen of the United States, residing at Scobey, in the county of Sheridan and State 5 of Montana, have invented certain new and useful Improvements in Sheet-Guides for Cylinder-Presses, of which the following is a specification, reference being had to the accompanying drawings.

10 This invention relates to sheet guides for presses, and particularly to guides for feeding sheets in cylinder presses.

The general object of this invention is to provide improved means for guiding the 15 sheets for cylinder presses, and particularly to provide adjustable means for this purpose coacting with a graduated rule, whereby the adjustment of the guide may be quickly and readily secured.

20 A further object of the invention is to provide a device of this kind wherein the sheet guiding member proper may be shifted from a lefthand to a righthand position.

A further object is to provide a device 25 of this character in which the sheet guiding member may be readily released from its engagement with the feed board or readily engaged therewith.

Still another object is to provide a sheet 30 guiding member having sheet engaging fenders which are adapted to be turned down into or out of operative position and enables one to feed paper which has been wrinkled or curled.

35 Another object in this connection is to form these fingers or fenders of hard rubber composition, to thereby eliminate the generation of electricity as where metallic fenders or fingers are used.

40 A further object is to so construct the sheet engaging or guiding member proper that the sheet will not slip under the guiding member when being fed.

Still another object is to provide a feed 45 board having a transversely extending slot with a transversely extending metallic strip bent to provide substantially a dove-tailed channel, this strip being inserted in the groove of the feed board, the flat margins 50 of the strip being provided one with a scale for setting the guide member at the lefthand end of the feed board and the other margin with a scale for setting the guide member at the righthand end of the feed board.

55 And a further object in this connection is

to provide a rod or slide shiftable through the dove-tailed channel, this rod having an indicating member at one end coacting with the scales above referred to, there being a sheet engaging guide member which may be 60 engaged with said rod, either at one end or the other end of the rod, to thus provide for guiding the paper either by its right-hand edge or its lefthand edge.

Other objects will appear in the course 65 of the following description.

My invention is illustrated in the accompanying drawings, wherein:—

Figure 1 is a top plan of a feed board provided with my improved paper guiding 70 attachment;

Fig. 2 is a longitudinal fragmentary sectional view through the board and channel and the latch end of the paper guiding rod;

Fig. 3 is a section on the line 3—3 of 75 Fig. 1;

Fig. 4 is a fragmentary vertical sectional view through the channel, a portion of the feed rod and the paper guiding block;

Fig. 5 is a transverse section on the line 80 5—5 of Fig. 4;

Fig. 6 is a perspective view of the paper guiding block; and

Fig. 7 is a fragmentary perspective view of a portion of the rod 17 and the head 19. 85

Referring to these drawings, 10 designates the feed board of a cylinder press, 11 designating the feed edge of the board, that is, the edge which is adjacent the cylinder. The feed board is longitudinally grooved 90 as at 12 for its entire extent, this groove, as illustrated, being rectangular in cross section and the face of the feed board, on each side of the groove, is chamfered as at 13. Disposed within this groove is a strip of metal, 95 designated generally 14, which, as illustrated in Fig. 3, is bent to provide a longitudinally extending channel 15 having laterally extending wings or margins 16, these wings or margins being received within the chamfers 13. The channel 15 has its walls extending downwardly and laterally from the junction of the channel with the wings and then extending downward and centrally, and then parallel to the bottom of the groove 12. 105 In other words, the sides of the channel are formed with overhanging walls.

The wings 16 are graduated to provide two scales designated A and B. The graduations on these scales are preferably 1/72 of 110

- an inch apart, and each scale is divided into 6" lengths, designated by the numerals 1, 2, 3 and 4. The scale B has its numerals 1, 2, 3 and 4 extending in a direction from left to right, while the scale A has its numerals extending from right to left, or reversely to the scale B. The scales A and B extend from the middle of the channeled strip 14 toward one end thereof, the remainder of the strip not being provided with indicating characters or graduations. The middle of the strip is indicated by the letter X in the drawing and this point is disposed exactly on a line with the middle of the feed board.
- 10 The strip is held to the feed board by means of screws or any other suitable devices of this character and the top of the strip is, of course, flush with the upper face of the feed board.
- 15 Slidably disposed within the strip is an elongated slide, designated 17, having the form of a rod, whose width for the greater portion of its length is slightly less than the mouth of the channeled strip 14, but 20 whose ends are wider and fit within the channeled strip, these end portions 18 and 19, which I will hereafter term heads, being approximately hexagonal in cross section so as to fit the channeled strip and extend beneath the overhanging side walls thereof so that they will have interlocking sliding engagement with the strip, the slide or sliding rod 17 having its upper face flush with the upper face of the channel strip 14.
- 25 At one end of the slide 17 there is disposed a latch device to hold the slide in adjusted position within the channel and as illustrated, this latch device comprises a strip of resilient metal, designated 20, this strip being riveted at one end to the rod 17 inward of the head 18 and extending beneath this head and then extending upward as at 20^a and angularly bent to form a thumb piece 21 whereby the spring may be raised.
- 30 The heads 18 and 19 are both somewhat shallower than the channel 15 but the spring 20 rests upon the bottom of the channel and urges the head 18 up against the overhanging walls of the channel so as to bind the head 18 and therefore the rod 17 in place and thus hold the slide or rod 17 in its adjusted positions. When it is desired to release the slide so as to permit it to be shifted along the channel, the spring 20 is 35 raised by the thumb piece 21 and this permits of this shifting movement. The head 18 and the head 19 are both provided with a pair of vertically extending perforations or sockets 22, as illustrated best in Fig. 2.
- 40 Coacting with the heads 18 and 19 is a guide block 23 which forms the paper guiding member. This guide block has on its under face the downwardly projecting pins or studs 24 which may be disposed in the 45 sockets 22 of either head. It is to be noted

that one of these pins 24 is flush with the inside face 25 of the guide block. The guide block is provided upon its upper face with a pair of ears 26 and pivotally supported between these ears is an arm 27 having a cross head 28 at its outer end. The extremities of this cross head are slotted and disposed in these slots are the curved fingers or fenders 29 which are preferably made of hard rubber composition and have a certain degree of resilience. When the arm 27 is turned into a position approximately parallel to the upper face of the guide block 23, these fingers 29 extend downward laterally on each side of the guide block, as illustrated in Fig. 1, so as to engage a sheet of paper and hold it down upon the feed board. For the purpose of adjusting the pressure exerted by these fingers 29, I provide an adjusting screw 30 which passes through the arm 27 and engages the upper face of the guide block. Thus the degree of pressure exerted by these fingers can be readily controlled.

In the practical use of this invention, the sheet guide is adjusted by shifting the slide 17 along the channel 15 using the inner end face of the head 18 as the index to coact with the scales A or B. When this index mark 31 is where it should be for the length of the sheet intended to be fed, the spring 20 is released and securely locks the slide rod from any movement due to the jar or vibration of the press. If it be desired to use a left hand guide, as for instance on a "work and turn run", it is only necessary to place the guide block on the head 18 with the face 25 of the guide block facing toward the right-hand end of the feed table. The scale B is for a righthand feed and the scale A for a lefthand feed. If it is desired to feed a sheet one foot long on a "work and turn job" the indicator would be set for the righthand guide in Fig. 1 using the scale B and for feeding the other side of the same sheet, the lefthand guide would be used and the guide block would be disposed on the head 18. As I stated before, each scale A and B is divided into 6" lengths but this indicates 6" on each side of the center or middle X so that the length indicated on the scale is doubled and thus while the numeral 1, for instance, of the scale A is but 6" from the middle X, yet when the indicating line is disposed at this numeral 1 on the scale A, it is set for a one foot sheet. It will be seen, therefore, that the guide block may be disposed either at the righthand side or at the lefthand side and that it is just as easy to set the device for the righthand guide as for the lefthand guide, the only difference being that different scales are used.

It is to be understood that the operative feeding the press stands at the end marked 130

Y in Fig. 1 and that the sheets to be printed are fed against the member 23 at the opposite end of the feed board marked Z, that is, if the operative is using a "righthand" feed. The indicator in Fig. 1 is set to properly guide a sheet two feet long and if it was a "work and turn" job, that is, a job where one side of the sheet is printed and then the sheet is turned over and the other side printed, all that would be necessary to do in order to feed the sheet with its other side turned up and to a "lefthand" feed would be to lift off the guide block 23 from its position on the bar 17 illustrated in Fig. 1, and replace it with its two pins in the openings 22 of the head 18. This would then set the guide block for a lefthand feed for this same sheet, that is, a feed against a guide which is disposed at the lefthand of the sheet. The reason for using two scales is because it is confusing to use even a common foot rule scale backward, and in order to avoid this confusion and thereby gain time and secure accuracy, the scale B is used for a righthand feed and the scale A is used for a lefthand feed. As the operative stands at the end marked Y he is able to readily read either one of the scales and set the guide either way by reference to the proper scales. For instance, if it be desired to feed a sheet one foot long, the indicating mark 31 would be disposed on the numeral 1 of scale B and this would bring the guide block 23 within one foot of the middle point X of the table and if it were desired to use a lefthand feed for the same sheet, the indicating mark 31 would be set in alinement with the numeral 1 of the scale A and the guide block 23 would be lifted out and placed upon the head 18 giving exactly the same feed and distance on the lefthand side as was before had on the righthand side, without in any way confusing the press feeder.

One of the minor advantages of my construction resides in the use of the fenders or fingers 29 which enables one to feed paper that has been wrinkled or curled these fenders bringing just enough pressure on the paper to afford a flat feed edge to the guide which insures a perfect register. When a perfect register is not desired, the arm 27 may be turned back over the block as illustrated in Fig. 6. It will be noted, as previously referred to, that one of the pins 24 is disposed flush with the inner face of the guide block. This is to prevent paper from slipping under the block when fed as it otherwise would be liable to do. Under ordinary circumstances, this feed guide is approximately 48" in length so that sheets of paper up to 24" can be guided. It is obvious, however, that the guide may be made longer or shorter than this, depending upon the size of the press and to accommodate sheets of paper of various sizes.

Having described my invention, what I claim is:

1. A feed board for presses having a transverse channel, there being graduations on one side of the channel, and a sheet guide sliding in said channel and coacting with the graduations and having means whereby it may be held at any desired point along the channel, said guide including a rod disposed in and having its upper face flush with the face of the feed board, said rod having an index mark at one end coacting with the graduations, and a sheet guiding head at the other end extending above the upper face of the rod. 80

2. A feed board for presses formed with a transverse channel, a feed guide sliding in said channel and having an index member coacting with the graduations, and a spring mounted upon the feed guide and resiliently urged against one wall of the channel to thereby hold the guide in adjusted positions, the spring being manually shiftable out of engagement to permit the shifting of the guide. 90

3. A feed board of a press having a transverse channel, there being a graduated scale on one side of the channel, a feed guide comprising a sliding rod disposed in said channels, and a guide block engageable with either end of the feed rod. 95

4. A feed board of a press having a transverse channel, there being a scale on one side of the channel, a feed guide comprising a sliding rod disposed in said channels, a guide block engageable with either end of the feed rod, and a holding device mounted upon the guide rod and adapted to engage the walls of the channel, to thereby prevent accidental movement of the slide rod. 100

5. A feed board of a press having a transversely extending channel in its face, there being graduations on the margins of the channel to form scales, the graduations of one scale reading reversely to the graduations on the other scale, a slide rod disposed in said channel and having heads at its opposite ends, one of said heads forming an index point coacting with said scales, means for locking the slide rod in adjusted position within the channel, and a guide block having detachable engagement with either end of said heads. 110

6. A feed board of a press having a transversely extending channel in its face, there being graduations on the margins of the channel to form scales, the graduations of one scale being reverse to the graduations on the other scale, a slide rod disposed in said channel and having heads at its opposite ends, one of said heads forming an index point coacting with said scales, means for locking the slide rod in adjusted position within the channel, said heads having vertical sockets, and a guide block having 130

- pins insertible into the sockets of either head.
7. A feed board of a press having a transversely extending groove therein, a 5 channel strip disposed in said groove and having overhanging side walls, a sliding paper guide disposed within said channel and having portions thereof extending beneath said overhanging walls of the channel, 10 and a leaf spring attached to the under side of said sliding guide at one end thereof and extending beyond the sliding guide and then upward and there formed with a thumb piece, said spring bearing resiliently against the bottom of the channel to thereby hold 15 the sliding guide in place.
8. A feed board for presses having a transversely extending channel in its face, and a paper guide longitudinally adjustable 20 in the channel and including a guide member, against which the edge of the paper is to be disposed and carrying means disposed to extend on each side of the channel for pressing out the wrinkled edge of the paper 25 sheet.
9. A feed board for presses having a transversely extending channel in its face, and a paper guide longitudinally adjustable in the channel and including a guide member, 30 against which the edge of the paper is to be disposed, carrying means for pressing out the wrinkled edge of the paper sheet, said means including a pair of parallel, laterally spaced, downwardly and laterally 35 curved resilient fingers.
10. A feed board for presses having a transversely extending channel in its face, and a paper guide longitudinally adjustable in the channel and including a guide member, 40 against which the edge of the paper is to be disposed, carrying means for pressing out the wrinkled edge of the paper sheet, said means including a pair of parallel downwardly and laterally curved resilient 45 fingers, of rubber composition.
11. A feed board for presses having a transversely extending channel in its face, a paper guide longitudinally adjustable in the channel and including a guide member, 50 against which the edge of the paper is to be disposed, carrying means for pressing out the wrinkled edge of the paper sheet, said means comprising an arm pivoted upon the 55 guide member for movement into or out of parallel relation to the table, means for vertically adjusting the arm, and resilient paper engaging fingers carried by the arm disposed in parallel relation and spaced from each other a distance equal to the 60 width of said member.
12. A feed board of a press having a transverse groove across its face, a metallic strip bent to form a channel disposed in said groove, the channel having overhanging side 65 walls and laterally disposed wings, the upper faces of the wings for half the length of the channeled strip carrying graduations, the graduations on one wing reading 70 reversely to the graduations on the other wing, the inner end of said graduated portion of the strip being disposed at the middle of the feed board, a slide disposed in the channel comprising a rod having heads at its opposite ends fitting beneath the overhanging walls of the channel, the upper faces of 75 the heads having sockets and the inner edge of one of said heads constituting an index coacting with said graduations, and a guiding block having pins upon its under face adapted to be disposed in the sockets of 80 either head to thereby permit the block to be shifted from one end of the slide to the other, one of said pins being disposed flush with the inner face of the block.
13. A feed board of a press having a 85 transverse groove across its face, a metallic strip bent to form a channel disposed in said groove, the channel having overhanging side walls and laterally disposed wings, the upper faces of the wings for half the length 90 of the channeled strip carrying graduations, the graduations on one wing reading reversely to the graduations on the other wing, the inner end of said graduated portion of the strip being disposed at the middle of the 95 feed board, a slide disposed in the channel comprising a rod having heads at its opposite ends fitting beneath the overhanging walls of the channel, the upper faces of the heads having sockets and the inner edge of 100 one of said heads constituting an index coacting with said graduations, and a guiding block having pins upon its under face adapted to be disposed in the sockets of either head to thereby permit the block to 105 be shifted from one end of the slide to the other, one of said pins being disposed flush with the inner face of the block, an arm mounted upon the top of the block and having downwardly and laterally curved resilient 110 fingers engaging on each side of the block, and means for adjusting the pressure of said fingers.
14. A feed board for presses having a transversely extending channel in its upper 115 face, the margins of the channel being provided with series of graduations, one series of graduations reading from the middle of the feed board to the right and the other series of graduations being in alinement 120 with the first named series but reading from the end of the feed board to the middle thereof, a rod slidably disposed in said channel and having a length greater than the length of the graduated portion of the channel, the rod being formed at its offset ends with heads, the distance between said heads 125 being equal to the length of the graduated

- portion of the channel, and a guide member detachably engageable with either of said heads.
15. A feed board of a press having a transverse channel, a feed guide comprising a sliding rod disposed in said channel, a guide block engageable with either end of the feed rod, and a scale on one margin of the channel with which the feed guide 10 acts.
16. A feed board for presses having a transversely extending channel, there being graduations on the margin of the channel extending from the middle of the feed board.

toward one end thereof, the graduations on one side of the channel being reverse to the graduations on the opposite side, and a feed guide comprising a sliding rod disposed in said channel having a head at one end provided with an index mark, and a guide block engageable with either end of the feed rod.

In testimony whereof I hereunto affix my signature in the presence of two witnesses.

HERBERT ROTHWILL.
